FUEL BURNING RADIANT AND AIR HEATER

Howard L. Bourner, Nashville, Tenn., assignor to Temco, Inc., Nashville, Tenn., a corporation of Tennessee

Application September 17, 1953, Serial No. 380,753

3 Claims. (Cl. 126—89)

This invention pertains to heaters and particularly to space heaters.

A primary object of this invention is to provide an improved heater which will directly radiate heat and will also heat air which by convection currents will distribute heated air throughout the room or space in which the heater is placed.

A further object of the invention is to provide a heater as in the preceding object and wherein means are provided for maintaining the outer surfaces of the unit cool enough so that no damage will be caused by articles or persons coming in contact with the surfaces of the unit.

A further object of the invention is to provide an improved method of maintaining the surfaces of the heater cool by heat exchange into air moving in a plurality of passageways extending from the bottom front of the heater to the top front thereof, the passageways being progressively removed from the source of heat so that the final passageway carries air which removes substantially all of the heat which would otherwise reach the outer surfaces and heat them.

It is a further object of the invention, in keeping with the foregoing object, to so position the passageway which moves the greater amount of air as to have its intake opening spaced considerably above the floor on which the heater stands, with the passageway moving a lesser amount of air nearer the floor, so that the more rapidly moving air, which will be inclined to pick up more dust from the floor, will be removed from the floor so as to avoid this disadvantage.

It is a further object of the invention to provide a space heater having air intake at the bottom front of the unit primarily through a screen panel, and an air outlet at the top front of the unit through a second screen panel, a space for direct radiation from ceramic radiants being provided between the upper and lower screen panels.

Further objects and the entire scope of the invention will be in part expressed and in part obvious from the following detailed description.

The invention may be best understood with reference to the accompanying drawings wherein:

Figure 1 shows a front elevational view of an assembled heater according to the invention.

Figure 2 shows a right-hand side view of the heater of Figure 1.

Figure 3 shows a top view of the heater of Figure 1.

Figure 4 shows a top sectional view taken substantially along the line 4—4 of Figure 1.

Figure 5 shows a side sectional view taken substantially along the line 5—5 of Figure 1, and

Figure 6 shows a front elevational view of a heater unit which comprises a part of the complete assembly shown in Figures 1—5.

The complete space heater consists basically of a casing or cabinet in which is removably supported a heater unit. The casing includes a top wall 10 and side walls 12 and 14, the latter extending downwardly to terminate at the floor 16 on which the complete heater will rest.

No bottom, front or rear walls are provided, but the lowermost ends of the side walls 12 and 14 are joined together at the rear by angle iron support 17. An inturned edge 18 extends completely along the front edges of top wall 10 and side walls 12 and 14. Additionally, a continuous inturned edge 20 extends along the rear edges of top wall 10 and side walls 12 and 14.

At the front of the casing there is provided a lower screen frame 22 and an upper screen frame 24. Both may be identical in construction, and the details of frame 24 will be described. Frame 24 consists primarily of a rectangularly formed edge member 26 which is generally U-shaped in cross-section, as may be most readily observed in Figures 4 and 5. A screen member 28, which may be conveniently bowed outwardly as desired to give a pleasing curvature, is fixed along the outer edge of the rectangular frame member 26. The rear edge of the member 26 is designated 30 and at the side edges is intended to mate with the inturned edges 18 of side walls 12 and 14. Apertures are provided through which bolts or rivets may be passed, or the members may be spot-welded together, to maintain the frame 24 in position on the upper front of the casing, all as will be readily observed from the several figures.

The side wall 12 of the casing is provided with an access door 32 for permitting manipulation of the burner controls, as will be fully described hereinbelow.

It may be noted that the lower screen frame 22 by virtue of being fastened to the lower portions of the inturned edges 18 of side walls 12 and 14 will serve to provide a lateral support for the lower front of the casing. Thus, at this point it will be clear that a simple and yet rugged casing is provided. This is a unit of manufacture, into which the heater unit per se may be inserted from the rear.

Referring now particularly to Figures 4—6 the heater unit is characterized by side panels 40 and 42, a rear panel 44 and a top panel 46. Extending between the side panels 40 and 42 is an inner air deflecting panel 48 and an outer air deflecting panel 50. The inner air deflecting panel extends from a lowermost point 48' at the bottom front of the unit to an upper point 48" near the upper front of the heater unit. The outer deflecting panel 50 similarly extends from a lower point 50' to an upper point 50" within the screen frame 24 at the upper front of the casing. A passageway 52 is formed between the inner air deflecting panel 48 and the outer air deflecting panel 50 and between side panels 40 and 42. This passageway, as will be clear from Figure 5, extends inwardly in a horizontal direction at the bottom of the unit, then curves upwardly and near the top of the unit turns again outwardly in a horizontal direction.

A second air passage 54 is defined between outer surface of outer deflecting panel 50 and the inner surface of rear panel 44. This passage will permit air to enter the bottom of the casing below the screen frame 22 and then pass between the heater unit side panels 40 and 42 upwardly and then out either an opening 56 between the top edge 44' of the rear panel and the rear extremity 46' of the top panel 46, or forwardly out an opening 58 between the terminal 50" of the air deflector panel 50 and the forward edge 46" of the top panel 46.

To maintain heat exchange with moving air laterally of the heater unit, side convection panels 60 and 62 are provided. These panels are similar in all respects and, referring to panel 60, there is provided top inturned edge 64, rear inturned edge 66 (Fig. 4) and a front inturned edge 68 which extends from the lower edge 60' of the panel 60 up approximately two-thirds of the panel 60 to an edge 68'.

In the region of panel 60 between the level of edge 68' and the top inturned edge 64 a wing 70 extends forwardly

(Figs. 4 and 5) to provide air directing means extending into the area of screen frame 24.

From the foregoing it will be apparent that air passages 72 and 74 are provided for the movement of air upwardly for heat exchange purposes along the side panels 40 and 42 and thence outwardly through the screen frame 24. In this way the side walls 12 and 14 of the casing are maintained in cool condition. It will be further observed that space exists outwardly of convection panels 60 and 62 and casing walls 12 and 14 for additional movement of air for maintaining the walls 12 and 14 in cool condition.

A hearth shelf 80 is provided extending between the heater unit side panels 40 and 42, this panel extending from a forwardly and downwardly turned edge 80' at the forward edges of side panels 40 and 42 to an inner formed rib 82. Extending downwardly and forwardly from rib 82 is a burner shield 84, the latter also extending the complete distance between side panels 40 and 42. The rib 82 lies approximately one-half the distance between the front edges of panels 40 and 42 and the inner air deflecting panel 48, all as may be most readily observed in Figure 5. It will be further noted in Figures 5 and 6 that the hearth shelf 80 is positioned at the level of the top of screen frame 22.

At substantially the level of hearth shelf 80, but spaced inwardly therefrom and near the inner air deflecting panel 48, is a support rail 86 extending between the side panels 40 and 42. Rail 86 is characterized by a trough section 88 for supporting the rear legs on ceramic radiants the main portions of which rest on the top of rib 82, all as shown in Figure 5. It will be understood that a plurality of conventional radiants will be provided, for extending completely across the space between side panels 40 and 42.

Resting on hearth shelf 80 is a hearth radiation reflector 94, preferably at least coated with a material which may be highly polished to reflect heat from the ceramic radiants 90. Additionally, side radiation reflectors 96 and 98 having polished surfaces may be provided for reflecting heat outwardly. Reflectors 96 and 98 may be seated in clips 100 fixed to the heater unit side panels 40 and 42 as shown in Figures 5 and 6. The forward edges of reflectors 96 and 98 may be sprung behind the inturned edges 18 of the casing side panels 12 and 14, as shown in Figure 4.

It will be noted that the ceramic radiants 90 extend upwardly to substantially the level of the lower edge of screen frame 24.

Apertures 110 may be provided on the outer side edges of rear panel 44 for mounting panel 44 on the inturned edges 20 of casing side walls 12 and 14. By means of self-tapping sheet metal screws extending through apertures 110 and corresponding apertures in edges 20, the entire heater unit as illustrated in Figure 6 may be maintained in position within the casing defined by top wall 10, side walls 12 and 14 and screen frames 22 and 24.

The heater unit is further provided with a combustion burner 120. This burner may be of conventional internal design and details are not thought to be necessary. However, it may be briefly noted that an air mixing arrangement is provided at 122 and combustion occurs at the plurality of outlets 124. Necessary control valves may be provided at 126 and a pipe for attachment to a source of fuel supply is provided at 128, extending rearwardly through a suitable aperture 130 in the rear panel 44. It will be noted that the position of the control means 126 is in proximity to the access door 32 shown in Figure 2. Thus, notwithstanding that the combustion burner is part of the heater unit as separately mounted in the casing, nevertheless the position of the door 32 provides ready access to the controls. It will be further understood that any convenient automatic pilot light arrangement may be provided, although same

is not shown in the drawings, for operation of the burner under control of a thermostat or the like.

The combustion burner 120 is installed in the heater unit as shown after same is assembled, by providing an aperture 132 in side wall 40 for permitting passage of the complete burner 120 therethrough. A small aperture 134 may be provided in opposite panel 42 for receiving an extension 120' of burner 120. After the burner 120 is inserted into the heater unit and fixed to side panel 40 by means of support screws 136, the upper portion of the aperture 132 may be covered by plate 138 which provides a suitable mounting structure for a pilot device and for preventing any undesired and substantial amount of air from entering the area of combustion from the side.

When required by city codes, a so-called dress guard 140 (Figs. 1 and 2) may be provided. This guard may be secured to the heater casing in any convenient manner, as by springing the ends of leg members 142 (Fig. 2) into suitable apertures (not shown) in the bottom of screen frame 24 and top of screen frame 22.

In operation suitable fuel will be introduced through pipe 128 and combustion will occur at the top of combustion burner 120, at the plurality of combustion apertures 124, all in conventional manner. The flame will cause the radiants 90 to become incandescent in the customary manner. Radiation will be directed outwardly with the aid of the hearth reflecting surface 94 and side reflectors 96 and 98. The primary air for combustion will enter through the mixing device 122' of burner 120. However, the secondary air for combustion will enter through screen frame 22 generally between the level of end 48' of inner air deflector 48, and the level of hearth 80. The burner shield 84 is provided to insure a generally upward flow of air about the burner combustion apertures 124.

There will be a large amount of heated air passing upwardly through and behind the ceramic radiants 90 and this air is directed outwardly generally through the lower half of screen frame 24, as will be fully apparent from Figure 5. It is an important aspect of the invention that this body of air, being heated, will move most rapidly. Moving rapidly, if the movement occurred near the floor 16 on which the heater stands, there would be a tendency to pick up considerable amounts of lint and other foreign objects, all which preferably should not be in the heated air. However, the intake for this large volume of heated air is considerably removed from the floor, being above the terminal point 48' of air deflector 48. Therefore, this objection found in known heaters is greatly reduced.

As has been indicated generally hereinabove, the next most rapid movement of air occurs through passageway 52 defined by the inner air deflector 48 and the outer air deflector 50. However, again the inlet to passageway 52 is considerably above the floor 16. To provide the final heat exchange to maintain the outer surfaces of the cabinet in cool condition, air moves through the passageway 54. While the intake to this passageway is generally at the floor level, nevertheless the movement of air in this passageway is quite slow and no appreciable amount of foreign material will be picked up from the floor.

Thus, from the foregoing description it is thought to be clear that by the present invention there is provided a highly efficient space heater, in which the outer surfaces 65 of the casing or cabinet are maintained cool, and yet foreign matter is not picked up from the floor of the room in which it stands, to contaminate the heated air.

What is claimed is:

1. In a space heater, the combination comprising an outer casing having top, rear, and side walls, the lower ends of said rear and side walls being formed to be mounted on a floor, and the front of said casing being open; inner side and top panels mounted within said outer casing in spaced relation to said side and top walls, respectively, of the outer casing; an elongated combustion

burner mounted between said side walls to extend transversely within the lower central portion of the casing; radiant means mounted to extend directly above said combustion burner; an elongated U-shaped outer air deflection panel having a lower portion extending rearwardly beneath said burner from a region near the lower open front of the casing, and having an intermediate portion extending upwardly at the rear of said burner in forwardly spaced relation to said rear wall, and having a top portion extending forwardly over said burner below, and in spaced relation to, said top panel, and terminating at a region near the upper open front of the casing; an elongated U-shaped inner air deflection panel disposed between said burner and said outer air deflection panel, and spaced from each, said inner air deflection panel having a lower portion extending rearwardly beneath said burner from a region near the lower open front of the casing, and having an intermediate portion extending upwardly at the rear of said burner, and having a top portion extending forwardly over said burner and terminating at a region near the upper open front of the casing; said outer air deflection panel and said inner air deflection panel having their side edges contiguous to the inner faces of said side panels; a horizontal hearth shelf extending laterally between said side panels and having a rear edge spaced from said inner air deflection panel; said lower portion of said outer air deflection panel being spaced above the plane of the lower extremity of said casing and forming with said side walls and the open front of said casing a lower air inlet opening; said top portion of said outer air deflection panel, said top panel, and said side panels forming with the open front of said casing an upper air outlet opening; said lower portions of said inner and outer air deflection panels and said side panels forming with the open front of the casing an intermediate air inlet opening; said top portions of said inner and outer air deflection panels and said side panels forming with the open front of the casing an intermediate air outlet opening; said hearth shelf, said lower portion of said inner air deflection panel, and said side panels forming with the open front of said casing an upper air inlet opening; said top portion of said inner air deflection panel and said side panels forming with the open front of the casing a lower air outlet opening; the lower portion of the inner air deflection panel and said hearth shelf defining with said side panels a passage from said upper air inlet

opening for secondary combustion air passing to and past said burner and said radiant means and to said lower air outlet opening; the inner and outer air deflection panels defining with said side panels a passage from said intermediate air inlet opening for first heat exchange air passing upward and behind said burner to said intermediate air outlet opening; said outer deflection panel and said rear walls and top panels defining with said side panels a passage from said lower air inlet opening for second heat exchange air passing upward and behind said first heat exchange air passage to said upper air outlet opening, said last mentioned passage being always separated from said secondary combustion air passage by the first heat exchange air passage whereby said second heat exchange air passage is always insulated by the air within the first heat exchange passage from the heat of said secondary combustion air passage, and will always contain air having a lower temperature, moving at a lower velocity, than either the first heat exchange passage air or the secondary combustion air passage air.

2. Apparatus as in claim 1 wherein air convection panels are mounted outwardly of, and in spaced relation to, said side panels to define side heat exchange air passages to receive air from said lower air inlet openings and for directing the air upwardly along the said side panels and then forwardly to the region of said lower and intermediate air outlet openings.

3. The structure defined in claim 2 in which the outer surfaces of said air convection panels and said casing side and rear walls define a second side heat exchange air passage for receiving air from said air inlet openings and for passing air to said air outlet openings.
